UNITED STATES PATENT OFFICE.

OSCAR KIESSIG, OF CHICAGO, ILLINOIS, ASSIGNOR OF ONE-HALF TO CHARLES F. CLARK, OF CHICAGO, ILLINOIS.

TOBACCO-PIPE.

1,037,493.

Specification of Letters Patent. Patented Sept. 3, 1912.

Application filed April 21, 1910, Serial No. 556,835. Renewed July 29, 1912. Serial No. 712,180.

To all whom it may concern:

Be it known that I, OSCAR KIESSIG, a citizen of the United States, residing at Chicago, in the county of Cook and State of Illinois, have invented a new and useful Improvement in Tobacco-Pipes, of which the following is a specification.

One of my objects is to provide improvements in tobacco-pipes to the end of preventing saliva from entering the bowl, and effectively trapping the nicotine and slugs for preventing them from being drawn through the mouth-piece; and another object is to provide a construction of pipe which may be readily cleansed.

Referring to the accompanying drawing—Figure 1 shows my improved pipe by a view in longitudinal vertical sectional elevation; Fig. 2 is a view like Fig. 1, with the mouth-piece and other removable, internal, parts omitted; Fig. 3 is a plan view of a removable and replaceable rod interposed between the bowl and mouth-piece of the pipe for trapping slugs and nicotine; Fig. 4 is a view in elevation of a nipple which co-operates with the mouth-piece for trapping the saliva; Fig. 5 is a section taken at the line 5 on Fig. 1 and viewed in the direction of the arrow; and Fig. 6 a section taken at the line 6 on Fig. 1 and viewed in the direction of the arrow.

The bowl of the pipe represented at 7 is formed integrally with a stem-section 8 which contains a longitudinally-extending bore 9 opening into the bowl as represented in Fig. 1 and provided with a lining 10 of non-absorbent material, such as metal, the lining preferably being in the form of a cylindrical tube which snugly fits the bore 9. Located in the lined-bore 9 is a rod 11, preferably of metal, and of general cylindrical shape, grooved between its ends at its top and bottom, as indicated at 12 and 13 respectively, and forming a web 14, perforated as indicated at 15, and connecting together the cylindrical shaped end-portions 16 and 17 of the rod. The effect of grooving the rod, as described, is that of affording between the walls of the grooves and the adjacent surfaces of the lining 10 upper and lower conduits 18 and 19, respectively, which are separated by the perforated web 14, which thus forms a partition, and communicate with each other through the perforations 15, the lower conduit 19 opening

into a passage 20 in the end 16 of the rod communicating with the interior of the bowl. The end 17 of the rod contains a longitudinally-extending groove 21 which opens into the conduit 18 and into a centrally-disposed passage 22 in a nipple 23 fitting into the shouldered end of the stem 8 and screwing upon the end 17 of the rod 11. The nipple is externally threaded at its outer end as indicated at 24, for connection with the internally screw-threaded end of a mouth-piece 25, the smoke-passage 26 therein being of relatively large diameter and formed with a pocket 27 for the purpose hereinafter explained. The nipple 23 terminates, beyond the point at which it is secured upon the mouth-piece, in a cone-shaped extension 28 which is spaced from the bottom of the pocket 27 as illustrated in Fig. 1 and through which the smoke is drawn into the mouth-piece.

When the pipe is in use the smoke passes from the bowl 7 through the passage 20, into the conduit 19, thence upward through the perforations 15 into the conduit 18, from which latter conduit it is drawn out of the mouth-piece through the passages 21 and 22. The perforated partition 15 permits of the free passage of the smoke from the conduit 19 to the conduit 18, but operates as a barrier for preventing passage into the conduit 18 of slugs or nicotine drawn into the conduit 19, the nicotine and slugs thus depositing on the walls of the conduit 19. Thus when accumulations in the pipe render cleaning thereof desirable, such cleaning may be effected by withdrawing the rod 11 from the lined-bore 9, the inner end walls of the grooves 12 and 13 serving to scrape from the lining 10 accumulations thereon or slugs and nicotine. The rod may then be cleaned in any desirable manner.

By constructing the nipple 23 and mouth-piece 27 as described, saliva entering the bore 26 in the mouth-piece will flow into the pocket 27 and be trapped therein against its entry into the passage 22 in the nipple, and thus the objectionable accumulation of saliva in the smoke-passages and the bowl is prevented.

The lining 10 of non-absorbent material is provided for the purpose of preventing the nicotine from soaking into the stem-section 8 and preventing discoloration thereof.

If desired the passage through the nipple

may be filled with absorbent material, such as cotton, for filtering the smoke before it passes to the mouth-piece, whereby any remnant of nicotine and moisture in the smoke will be removed.

While I have illustrated and described my invention as embodied in a pipe, I do not want to be understood as intending to limit it to its use in this connection, as it may be embodied, or used to advantage in cigar-holders and the like articles.

What I claim as new and desire to secure by Letters Patent is—

1. A pipe comprising a bowl, a stem connected with the bowl and provided with a mouth-piece, a removable and replaceable rod in the bore of said stem containing longitudinally-extending grooves, with the portion of the rod separating said grooves perforated, said grooves forming with the wall of said bore longitudinally-extending conduits therein, one end of said rod containing a passage connecting with the interior of the bowl and with one of said conduits, and the opposite end of said rod containing a passage connecting with the other of said conduits and with said mouth-piece, for the purpose set forth.

2. A pipe comprising a bowl, a stem connected with the bowl and provided with a mouth-piece, a removable and replaceable

rod in the bore of said stem containing longitudinally-extending grooves in its top and bottom, with the portion of the rod separating said grooves perforated, said grooves forming with the wall of said bore longitudinally-extending conduits therein, one end of said rod containing a passage communicating with the interior of the bowl and with one of said conduits, and the opposite end of said rod containing a passage communicating with the other of said conduits and with said mouth-piece, for the purpose set forth.

3. In a device for the purpose set forth, the combination of a stem containing a longitudinally-extending bore, and a removable and replaceable rod in said bore provided with longitudinally-extending grooves separated by a perforated partition, said grooves forming with the wall of said bore longitudinally-extending conduits therein, one end of said rod containing a passage communicating with one of said conduits and with the inlet-end of said stem and the other end of said rod containing a passage communicating with the other of said conduits and with the outlet-end of said stem.

OSCAR KIESSIG.
